UNITED STATES PATENT OFFICE.

WILLIAM M. PARKER, OF PARKERSBURG, WEST VIRGINIA.

HOLDER FOR HEADED ARTICLES.

Application filed April 27, 1920. Serial No. 377,077.

To all whom it may concern:

Be it known that I, WILLIAM M. PARKER, of Parkersburg, in the county of Wood and State of West Virginia, have invented a new and useful Holder for Headed Articles, of which the following is a specification.

The main object of my invention is to provide an efficient holder or carrier for screws, nails or other headed articles.

10 My invention is especially useful in shipping devices such as electric switches where it is desired that screws accompany the switch so as to be handy for use in putting the switch in position, the screws heretofore having been put loose in the switch casing or in some relatively expensive receptacle.

This electric switch art is referred to merely as one example of the utility of my 20 device which, it will be clear later on, is applicable to many uses where screws, nails or other headed articles are involved.

25 My invention consists primarily in providing a cheap but efficient holder preferably arranged to hold the headed article in a vertical position.

30 A feature of my invention is a holder having a portion to engage the head of the article and thereby hold the latter in position.

Another feature consists in providing a portion to engage the head at one side of the article and another portion to engage the opposite side of the article.

35 Another feature consists in connecting together at intervals the portions between which the article rests so that partitions between the articles are provided.

Another feature is a holder comprising 40 two members attached together at intervals but permitting entrance of the shanks of the headed articles between the two members, the heads engaging one or both of the members to hold the articles in place.

45 Another feature of my invention consists in slitting one of the holding portions to receive the head of the article and in the case of a screw having the portion at the slit preferably enter the slit in the head of 50 the screw.

Another feature consists in perforating the holder at intervals so that the holder may be made in the form a strip or ribbon and the desired amount readily torn off.

55 Another feature consists in applying glue or other adhesive to the holder so that the

latter may be held in the desired location.

Other features will be described below.

In the drawing—

Fig. 1 is an elevation of a device embodying my invention;

Fig. 2 is a section thereof on line 2—2 of Figure 1;

Fig. 3 is an elevation of the reverse side of the strip shown in Figure 1;

Fig. 4 is a section on line 4—4 of Figure 1;

Fig. 5 is a plan view of the strip and screws shown in Figure 1;

Fig. 6 is a plan of a modification hereinafter described;

Fig. 7 is a section on line 7—7 of Figure 6;

Fig. 8 is an elevation of a modification hereinafter described;

Fig. 9 is a section on line 9—9 of Figure 8;

Figures 10 and 11 are elevations of other desirable forms described below.

As shown in the forms of Figures 1 to 5 my holder consists of two strips of paper A and B attached together by gum or otherwise at intervals as indicated by heavy lines at a, b, and c. The strips are also perforated at intervals as indicated at a', b' and c' so that any desired length of strip may be readily torn off it being my idea to have the strips of considerable length originally.

The rear strip A has a relatively large portion of its rear surface gummed as at A' so that the portion may be conveniently attached to the wall B' of an electric switch casing, for example, which will hold the strips in a vertical position.

In Figures 1 to 5 the front strip B has slits D, E and F extending lengthwise of the strip and I have shown two screws in position, the shanks H being retained in position between the strips A and B, and a portion of the heads K passing through the adjacent slit, the under side of the head engaging the bottom edge of the slit, thus holding the screw from falling. This method of holding would apply to nails also but in the case of the screw the top edge of the slit in the strip B enters the slit in the head of the screw and thereby furnishes additional means of holding the screw firmly in position. It will be understood that the strips are relatively thin so that between the attached portions they may be readily spread to receive the headed articles.

In the form of Figures 6 and 7 the member B² at one side of the shank is slotted and the top edge of the slit enters the slit in the head K of the screw H, the member A² being also slotted and the top edge of its slit entering the slit in the head K, the members A² and B² being connected together at intervals as already described in relation to the form of Figures 1 to 5.

10 In Figures 8 and 9, I illustrate another method of use and in this case the shank of the headed article is held between strips A³ and B³ but the bottom of the head rests upon the top edge of the strip B³.

15 In Figure 10, I have a holder in one piece having a portion A⁴ slotted to receive a portion of the head K and having another portion B⁴ which may engage the shank H. This form may be made of paper although 20 for some purposes it might be desirable to make it of cardboard or even stiffer material. In this form I preferably connect portions A⁴ and B⁴ together between the articles and perforate the connected portions as in the 25 other forms.

30 In Figure 11, I show a holder in one piece having a portion A⁵ slotted to receive one side of the head K and having another portion B⁵ slotted to receive the opposite side of the head. This form may be made of the material described in connection with the form of Figure 10 and may have portions A⁵ and B⁵ connected together at intervals and perforated as in the other forms.

35 It will be clear that I have provided a very efficient and at the same time a very cheap holder which may be made in long strips from which the desired length may be torn off or cut off depending on the number of headed articles to be held.

40 While it is preferable to attach the holder to some member which will keep the device in a vertical position yet my device will if otherwise used be of great value because the headed article will be securely held to the holder and therefore will not be lost and will be readily accessible.

45 What I claim is:

1. A holder for headed articles comprising two strips of flexible sheet material attached together at both sides of an unattached portion, one of the strips at the unattached portion being slit lengthwise of the strip and crosswise of the article, the slit being of such size that it will receive the 50 head of the headed article but will prevent movement of said head lengthwise of the strip.

2. A holder for screws comprising two strips of flexible sheet material attached together at both sides of an unattached portion, one of the strips at the unattached portion being slit lengthwise of the strip, the slit being of such size that it will receive the 60 head of the headed article, the upper 70 wall of the slit entering the slit in the head of the screw.

3. A holder for headed articles comprising two strips of flexible sheet material attached together at intervals and weakened 75 at the attached portions, one of the strips being slotted lengthwise of the strip at the unattached portions and one of the strips being adapted for attachment to a support so as to hold the holder in vertical position. 80

WILLIAM M. PARKER.
